UNITED STATES PATENT OFFICE

ROKURO KUROKAWA, OF SAN FRANCISCO, CALIFORNIA

DESIGN FOR A LAMP

Application filed January 30, 1931. Serial No. 38,503. Term of patent 14 years.

To all whom it may concern:

Be it known that I, ROKURO KUROKAWA, a subject of the Emperor of Japan, residing at the city and county of San Francisco and State of California, have invented a new, original, and ornamental Design for a Lamp, of which the following is a specification, reference being had to the accompanying drawing, forming part thereof.

Fig. 1 is a side elevation of my design for a lamp or article of similar nature.

Fig. 2 is a front view of the upper portion of Fig. 1 as seen from the line 2—2 thereof.

Fig. 3 is a horizontal cross section as seen from the line 3—3 of Fig. 1.

The shading on the figure denotes surface shading only.

I claim:

The ornamental design for a lamp substantially as shown and described.

ROKURO KUROKAWA
